MAGNETO

Application filed March 17, 1930. Serial No. 436,553.

This invention relates to magneto ignition systems.

Special objects of the invention are to provide a thoroughly efficient and practical magneto, which will be less expensive to build and maintain than the ordinary mechanical interrupter type of magneto, and which also will be less likely to get out of order.

The foregoing and other desirable objects 10 are attained by the novel features of construction, combinations and relations of parts hereinafter described, illustrated in the accompanying drawings and broadly covered in the claims.

15 Fig. 1 is a vertical sectional view illustrating one practical commercial embodiment of the invention; Fig. 2 is a broken part sectional detail view of one of the magnetic breaker units as viewed from the plane of line 2—2 of Fig. 1; Fig. 3 is a circuit diagram of the device shown in Fig. 1; Fig. 4 is another circuit diagram illustrating the provision of a plurality of the breaker units adapted to be selectively cut into or out of 20 service.

Referring to Figs. 1 and 3 of the drawings, it will be seen that in the present disclosure, the rotating member is in the form of a permanent U-magnet made up of the branches 30 N and S connected at one end by the back piece 5 and mounted on the shaft 6 by means of that back piece and by means of a non-magnetic bridge piece 8 at the opposite end. This permanent magnet is shown made up of 35 transverse laminations connected by through bolts 9, which serve to hold the assembly, including the end piece 8 in rigid united relation.

The field structure comprises in the illustration the pole pieces 10, 11, Fig. 3, connected at the top by the core piece 12 carrying the primary and secondary windings 13, 14. The field frame may be of laminated or solid construction and in the illustration, the parts 40 are shown connected by the screws 15, extending down through the ends of cross-piece 12, the end portions of the latter being undercut and shouldered as indicated at 16 to fit closely over the upper ends of the pole pieces.

50 A special and important feature of the in-

vention is that the break in the primary circuit is interrupted automatically, substantially at the peak of the wave by an electro-magnetic breaker unit shown generally at 17 in Fig. 1 and illustrated more in detail in 55 Figs. 2, 3 and 4. These latter views show the breaker is made up of an electro-magnetic coil 18 on a magnetic yoke structure 19, the latter having pole pieces 20, 21, separated to provide a gap 22 with which cooperates an 60 armature 23 carried by a lever 24. This armature lever has a contact portion 25 cooperating with a terminal 26. The breaker contacts are connected in the primary circuit by conductor 27 leading from one end 65 of the primary coil to the stationary breaker point 26, movable contact 25, armature lever 24, conductor 28 to one end of the breaker coil 18, the opposite end of said coil being suitably grounded as indicated at 29 and the 70 other end of the primary coil being grounded as indicated at 30, Fig. 3. A condenser 31 is bridged across the breaker points by a short conductor 32 connected with the terminal 33, the opposite side of said condenser being suitably grounded as indicated at 33' in Fig. 3. A suitable grounding switch is indicated at 34 in Fig. 3 connected by a conductor 35 with a suitably insulated brush 36 bearing on the terminal 33. This brush is shown in Fig. 1 75 as carried by the removable top 37 of the magneto casing, so that the removal of this top interrupts the control circuit of the magneto.

The armature of the electro-magnetic interrupter may be suitably tensioned to respond only to the peak or other desired sector of the current wave, the means for the purpose being shown as a compression spring 38 held engaged with the armature by a headed screw 39, whose position can be set by a nut 40, Fig. 2, the latter being accessible through an opening 41 in the top of the case.

The secondary circuit of the magneto is illustrated as by way of a conductor 42, spring 43, plunger 44 and brush 45 in a rotating distributor head 46 to the distributor segments 47 connected with the several spark plugs. This distributor is shown as oper- 100

ated from the magneto shaft by the usual two-to-one gearing 48.

To enable a quick change-over in the event of any failure in the electro-magnetic breaker, several of the breaker units may be employed, such as indicated at 17a, 17b in Fig. 4 and a selector switch be provided by which any one of such breakers may be cut into and out of service. In this particular illustration, each breaker is illustrated as double-ended and each operating two sets of independently connected breaker points, thus enabling two units to serve as four complete breakers. The extra breaker points are indicated at 25a, 26a and they are shown operating in conjunction with the magnetic gaps 22a similar to the gaps 22 but located at the opposite ends of the electro-magnetic units. In this particular case, the lead 27 from the primary of the magneto passes through the arm 49 of the selector switch and thence by way of any one of the switch contacts 50, 51, 52 and 53, through leads 27a, 27b, 27c, 27d to the four breaker contacts.

The selector switch 49 may be located at any convenient control point on the aircraft or other vehicle on which the magneto is used, so that in case of any failure or indication of failure of the magneto, a new interrupter may be instantly switched into operation. The condensers are preferably combined or built into the magnetic breaker units as by being located between the arms of the magnetic yoke (Fig. 2), so that in switching over, a new condenser will be brought into service. If desired, one condenser may be made to serve for both the sets of a double ended breaker unit, as indicated in Fig. 4, by connecting them through leads 32a direct to the line 27, instead of through the switch buttons 50, 51, etc.

Constructed as disclosed, the magneto can be produced quite inexpensively, since there are no cams, mechanically actuated breaker arms or other necessarily accurate and more or less delicate parts. The instant of break and hence the timing is determined automatically by the force of current generated in the machine and this timing is accurately determinable by varying the tension on the magnetically actuated breaker arm. The coil and breaker structures, with the short electrical connections are all disposed in the upper chamber 54 above the horizontal partition 55, which separates the lower rotor chamber from the upper space. Consequently, any difficulty with the transformer coil, the breaker mechanism or the connections, may be quickly remedied upon removal of the top cover 37. The magnetic breaker unit, or units, if there be more than one, may be removably fastened down in the upper chamber as by means of the screw fastenings indicated at 56.

What is claimed is:

1. In electrical ignition systems, a magneto comprising a rotating permanent magnet, a field structure in cooperative relation therewith and including a coil, an electromagnet connected in series relation with said coil, a circuit breaker for said coil actuated by said electromagnet and means for variably setting said circuit breaker to interrupt the coil circuit at the desired point in the current wave generated by the magneto. 70

2. In electric ignition systems, the combination of a magneto including relatively rotatable parts, one carrying primary and secondary coils, an electromagnet connected in series relation with said primary coil, a circuit breaker actuated by said electromagnet and connected to control the primary coil circuit and means for variably setting said circuit breaker to operate at a desired level 80 of the current wave generated by the magneto. 85

3. A magneto comprising a rotating permanent magnet, a field structure in cooperative relation therewith and including primary and secondary windings, a circuit breaker connected to interrupt the circuit of said primary coil, an electromagnet for actuating said circuit breaker and connected in series relation with the primary coil and means for variably setting said circuit breaker to operate at a desired level of the current wave generated by the magneto. 90

4. A magneto comprising a rotating permanent magnet, a field structure in cooperative relation therewith and including primary and secondary windings, a circuit breaker connected to interrupt the circuit of said primary coil, an electromagnet for actuating said circuit breaker and connected in series relation with the primary coil, means for variably setting said circuit breaker to operate at a desired level of the current wave generated by the magneto including a spring governing action of the circuit breaker by the electromagnet and an adjustable device for varying the force exerted by said spring. 100

5. A magneto comprising a case having lower and upper compartments, the upper compartment having a removable cover, a rotor journaled in the lower compartment, a field structure cooperating with said rotor and including transformer windings removably mounted in the upper compartment and an electromagnetic circuit breaker also removably mounted in the upper compartment connected with the transformer windings, whereby upon removal of the cover the transformer windings and electromagnetic circuit breaker are accessible for removal. 115

6. A magneto comprising cooperating field and rotor structures, a plurality of electromagnetic circuit breakers closely associated with the field structure and a remotely located control switch for selectively cutting 125 130

the electromagnetic circuit breakers into service relation with the field structure.

5 7. A magneto having transformer windings, electromagnetic circuit breakers for controlling the primary of the transformer windings and means for selectively cutting said electromagnetic circuit breakers into service relation.

10 8. In combination, a magneto having primary and secondary windings, electromagnetic circuit interrupters for the primary winding and means for interchangeably and selectively switching said electromagnetic circuit interrupters into series relation 15 with said primary winding.

15 9. A magneto comprising a permanent U-magnet mounted for rotation on an axis extending longitudinally of the same, pole pieces about the legs of said U-magnet, primary and secondary windings electrically associated with said pole pieces and an electro-magnetic circuit breaker controlling the circuit of the primary winding and connected to be actuated by the current generated in said primary 25 winding.

20 10. A magneto comprising a permanent U-magnet mounted for rotation on an axis extending longitudinally of the same, pole pieces about the legs of said U-magnet, primary and secondary windings electrically associated with said pole pieces, an electromagnetic circuit breaker controlling the circuit of the primary winding and connected to be actuated by the current generated in 30 said primary winding and including a breaker element and adjustable spring means for variably predetermining the timing of 35 operation of said breaker.

40 11. A magneto, comprising a field structure having pole pieces and provided with primary and secondary windings, a permanent U-magnet arranged to rotate between the pole pieces on an axis extending longitudinally of the same, said U-magnet being 45 rotatably supported at both ends and an electromagnetic interrupter for the primary winding connected to be electrically actuated by the current generated in the primary winding on the rotation of said U-magnet.

50 12. A magneto having a current generating winding, an electromagnetic breaker for said winding connected to be electrically actuated thereby, condensers and switch means for interchangeably connecting said condensers in service relation to said winding.

55 13. A magneto having a current generating winding, a plurality of breakers for said winding, a plurality of condensers and switch means for interchangeably connecting said breakers and condensers in service relation to the winding.

60 14. A magneto having a current generating winding, a plurality of condensers associated with said winding and means for selectively switching said condensers individually

into and out of service relation to said windings.

65 15. A magneto having primary and secondary windings, electromagnetic circuit controllers for said primary windings, condensers associated with said controllers and selector switch means for selectively connecting said electromagnetic controllers and condensers into and out of service relation to the primary winding.

70 16. A magneto having an electromagnetic breaker unit provided with two independently operating circuit breakers and means for selectively cutting said independent circuit breakers into and out of service relation.

75 17. A magneto having an electromagnetic breaker unit provided with two independently operating circuit breakers, means for selectively cutting said independent circuit breakers into and out of service relation and 80 a condenser connected in operative relation with both circuit breakers and therefore effective when either circuit breaker is in service.

85 18. A magneto having an electromagnetic breaker unit provided with magnetically 90 operated breakers at opposite ends of the same and means for independently switching said breakers into and out of service relation.

90 In testimony whereof I affix my signature. 95
JOSHUA STRUTHERS.
